UNITED STATES PATENT OFFICE.

EFFIE C. KUEBLER, OF CHICAGO, ILLINOIS.

GARMENT-SHIELD.

1,136,242.

Specification of Letters Patent. Patented Apr. 20, 1915.

Application filed August 2, 1912. Serial No. 712,916.

To all whom it may concern:

Be it known that I, EFFIE C. KUEBLER, a citizen of the United States, residing at Chicago, in the county of Cook and the State 5 of Illinois, have invented certain new and useful Improvements in Garment-Shields, of which the following is a specification.

This invention relates in general to wearing apparel and has more particular relation 10 to brassières, corsets or similar garments, one of its primary objects being to provide a shield adapted to be disposed over and completely cover the garment lacings or fastenings thereby adding to the attractiveness, 15 comfort and appearance of the garment.

Another object of the invention is to secure the shield to the garment by a yielding or flexible attachment so that the shield will completely cover the adjustable lacings and 20 also the fastenings in case the garment is provided with a floating strip, and will permit adjustment of the garment to various sizes, both at the top and bottom and will completely cover the lacings or fastenings 25 or both, irrespective of the width of the lacing opening and irrespective of the difference in width between the top and bottom of the lacing opening, thereby permitting adjustment of the garment to conform to 30 various figures without exposing the lacings or fastenings at the edge of the shield.

A further object is to so attach the shield to the garment that the shield will always lie 35 flat and cover and be disposed smoothly over the lacings or fastenings, irrespective of the degree of adjustment of the garment.

Other objects and many of the attendant 40 advantages of this invention will be readily apparent as the same becomes better understood, by reference to the following description when considered in connection with the accompanying drawings.

Referring to the drawings, Figure 1 is a perspective view showing one form of my 45 invention embodied in the back of a brassière; Fig. 2 is an enlarged view, showing more in detail the manner of attachment of the shield; Fig. 3 is an enlarged fragmentary view, the shield and a portion of the 50 garment being shown in section, and Fig. 4 is a view similar to Fig. 2, showing the modified manner of attaching the shield.

On the drawings reference character 1 designates the body of a brassière which has

been chosen in the present instance for purposes of illustration. It should be understood, however, that my invention is capable of application to corsets and other similar garments as well as to brassières and while I have shown, for purposes of illustration in 55 the present drawings, the shield as attached to the outside of the garment and serving as a cover to obstruct the lacings from view it should be understood that my invention is capable of application to a brassière, corset or other similar garment in any other position where it may be desirable to employ it.

In the present instance I have shown my improved shield as attached to the back of 70 the garment but I do not desire to limit myself to this construction as obviously it might be attached to the front or any portion of the garment where the fastenings or lacings are placed. In the form of garment 75 shown on the drawings the sides of the opening are provided with stiffening bone stays 2 to which the eyes 3 are attached, the lacings 4 threaded through the eyes being employed to adjustably connect the opposed 80 sides of the opening so that the width of the opening can be regulated throughout its length to conform the garment to the figure of any particular wearer. While the stiffening stays 2 are customarily employed it 85 should be understood that in some forms of garment these stays are omitted.

The shield or covering embodying my invention comprises a body portion 5 which may be made of any desirable material such, 90 for instance, as a suitably woven fabric or other preferred material. In the form of shield shown the fabric is folded and sewed adjacent each edge with two rows of stitching, one row being disposed at the margin 95 and the other spaced inwardly therefrom, providing thickened marginal portions 8 and 9 from the inner edges of which the attaching portions 6 and 7 project from the body of the shield. From Fig. 3 it will be 100 observed that the attaching portions 6 and 7 are secured to the body portion 5 along the inner edge of the marginal portions 8 and 9 by the inner rows of stitching. In the form of the invention shown in Figs. 1 to 3 inclusive the attaching portion 7 is secured by stitching or otherwise along its free edge 10 to the body of the garment adjacent

to the eyes 3. This manner of attachment leaves the attaching portion 7 extending from the edge 10 which is secured to the body of the garment to the point 11 where it is secured to the body of the shield, free to move about the edge 10 so that considerable latitude of relative movement between the shield and the body of the garment may take place without exposing the eyes 3 or 10 the lacings beyond the edge of the shield. The other edge of the shield may be attached to the body of the garment in any suitable manner. In Figs. 2 and 3 I have shown the attaching portion 6 as equipped 15 with hooks 11 adapted to engage with corresponding eyes 12 secured in corresponding position on the body of the garment. These eyes are positioned laterally of the lacing eyes, and in a garment provided with 20 a floating strip the eyes may be either on the floating strip or on the body of the garment at one side of the floating strip. In order to accommodate the shield to greater varieties of adjustment of the garment I 25 may, instead of mounting the hooks on the marginal portion 8, mount them on the attaching strip 6, this manner of positioning the hooks being illustrated in Fig. 4 where- 30 in a slightly different type of fastener in the form of button fasteners 13 is disclosed, one member of the fasteners, however, being mounted on the attaching strip 6.

It will be manifest that when the garment is laced substantially as shown in Fig. 3 the 35 attaching portions 6 and 7 will lie flat against the face of the garment and beneath the shield, thereby permitting the shield to be disposed flat and smoothly over the lacings and fasteners. Should the figure 40 of the wearer, to whom the garment is fitted, require a larger adjustment of the garment the lacings will be correspondingly loosened thereby increasing the width of the lacing opening. In this instance the edge 45 of the attaching strip 7 will move outwardly toward the edge of the shield without, however, disturbing the position of the shield which will still maintain its position over the lacings and fastenings and will lie flat and smoothly against the face of the garment. The attaching portion 7 is sufficiently 50 pliable to permit a wide variation in width of the lacing opening between the opposite ends thereof without disturbing the position 55 of the shield and the garment may therefore be adjusted at top or bottom to fit the figure of the wearer without displacing the shield and without exposing the lacings or fastenings beyond either edge of the shield. The marginal portion 9, which 60 is in reality a plait, serves to stiffen the edges of the shield and assist in maintaining it smooth and flat, the attaching portion 7 being sufficiently pliable to permit any 65 variation in position without disturbing or

displacing the shield. In some instances, however, it may be desirable to reinforce or add to the stiffening provided by the plait alone, and for this purpose any suitable stiffening means might be employed. 70

My improved shield, constructed and attached in the manner described, will always be disposed flatly and smoothly whether attached to the inside or outside of the garment, and by reason of its pliable connection 75 with the garment it will not be wrinkled or distorted either when in use or by any adjustment in size of the garment, which may be effected by adjustment of the lacing.

In Fig. 4 of the drawings I have shown 80 both the attaching portions 6 and 7 as being detachably secured to the garment. While in a garment made up at the factory with the shield attached, the manner of attachment shown in Fig. 3 will customarily be 85 employed, my invention contemplates the manufacture of the shield separately, as an article of manufacture to be sold independently and attached to any desired garment by detachable attaching means, as shown 90 in this figure.

It is believed that my invention and its manner of use will be fully understood from the foregoing without further description and it will be obvious that various modifications of the details disclosed may be resorted to without departing from the spirit of this invention or sacrificing any of its material advantages. 95

I claim:

1. The combination of a garment provided with an adjustable opening and having means for adjusting the size of said opening, a shield of suitable material shaped to overlie said opening and having a stiffened marginal portion along one longitudinal edge, a pliable strip of material attached along one edge to said shield at the inner edge of the stiffened marginal portion thereof and at its other edge to the garment at one side of said opening, said strip serving to connect the shield to the garment and being disposed within the perimeter of the shield between the shield and the garment, and means for attaching the free edge of said shield to the garment at the opposite side of said opening. 100

2. The combination of a garment provided with an adjustable opening, and having means for adjusting the size of said opening, a shield shaped to cover said opening, said shield having a stiffened marginal portion along one edge, means for permanently attaching said edge of the shield to the garment comprising a pliable member disposed between the garment and the shield, one edge thereof being attached to the shield at the inner edge of said stiffened portion and the other edge being attached to the garment body at one side of said opening, 110 115 120 125 130

and means for attaching the opposite edge of said shield to the garment at the opposite side of the opening.

3. A shield adapted to cover a variable width opening in a garment, consisting of a body portion of suitable material having a stiffened marginal portion, and a pliable attaching portion permanently secured to said body portion along the inner edge of said marginal portion so as to lie wholly within the perimeter of the shield whereby

said shield may be flexibly attached to a garment without exposing the attaching means to view.

In testimony whereof I have hereunto set my hand in presence of two subscribing witnesses.

EFFIE C. KUEBLER.
